United States Patent Office

Des. 201,083
Patented May 11, 1965

201,083

MODULAR ELECTRONIC POWER SUPPLY UNIT OR SIMILAR ARTICLE

Herbert Roth, 64—11 228th St., Bayside, N.Y.

Filed Nov. 21, 1963, Ser. No. 77,534

Term of patent 14 years

(Cl. D26—15)

FIG. 1

FIG. 2

FIG. 3

FIG. 4

FIG. 5

FIG. 1 is a front, top and right side perspective view of a modular electronic power supply unit or similar article, showing my new design,

FIG. 2 is a rear elevational view, to an enlarged scale,

FIG. 3 is a left side elevational view, to an enlarged scale,

FIG. 4 is a bottom plan view, to an enlarged scale, and

FIG. 5 is a top plan view thereof, to an enlarged scale.

The dominant features of my new design are shown in solid lines in the drawing.

I claim:

The ornamental design for a modular electronic

power supply unit or similar article, substantially as shown and described.
